UNITED STATES PATENT OFFICE.

GEORGE H. BARNHART, OF OURAY, COLORADO.

MAP FILE.

1,416,661.

Specification of Letters Patent. Patented May 16, 1922.

Application filed May 12, 1920. Serial No. 380,818.

To all whom it may concern:

Be it known that I, GEORGE H. BARNHART, a citizen of the United States, residing at Ouray, in the county of Ouray and State 5 of Colorado, have invented certain new and useful Improvements in Map Files, of which the following is a specification.

This invention relates to a filing cabinet for maps, drawings and other similar objects, and its primary object is to provide a cabinet of very practical though simple construction in which a number of maps, drawings, blue prints or other articles of the same kind may be arranged in an unfolded condition and so as to be readily accessible for separate removal.

Another object of the invention is to provide for use in cooperation with the holding members of the filing device, convenient 20 means by which any map or maps may be removed from the cabinet without disturbing the others, or by which one or more maps may be placed in a selected position with relation to others already on file.

Still another object of the invention is to provide a filing cabinet in which maps, drawings and the like are suspended for vertical filing with their upper edges in a common plane, and another object is to provide 30 a cabinet of the above described character which may include a plurality of separate filing units and which in its closed condition provides a dust-proof container of compact form suitable for use as a table or shelf 35 or as a support for a drawing board or the like.

With the above and other objects in view, all of which will fully appear in the course 40 of the following description, my invention in its preferred form consists of the construction and arrangement of parts shown in the accompanying drawings in the various views of which like parts are similarly designated, and in which—

Figure 1 represents a perspective fragmentary view of the cabinet in an open position;

Figure 2, a vertical section through the cabinet showing the use of the means employed in filing maps or other articles or removing those already filed;

Figure 3, a transverse section on the line 3—3, Figure 2;

Figure 4, a similar view of the cabinet in 55 its open condition;

Figure 5, an elevation of the upper portion of a map ready to be filed by the use of my invention, and

Figure 6, a face view of the two keepers cooperatively used in filing and removing 60 the maps.

Referring to the drawings by numerical reference characters, my improved filing cabinet in its preferred form is composed of a case 2 of suitable design and proportions 65 consisting of a bottom 3, a back 4, two parallel ends 5 and a top or lid 6 which is hinged at the upper edge of the back to protect the contents of the same from dust when not in use.

The top in its closed position may be employed as a table or drafting board and to this end can be made of any suitable size or form.

The ends of the case are rabbeted at their 75 upper edges to provide parallel ledges 7 for the sliding support of one or more upright plates 8 which divide the interior of the case into compartments 9 each adapted to receive a number of maps or other similar articles. 80

The foremost plate constitutes the front of the case and may be placed directly opposite the back of the same when the cabinet is composed of a single unit or it may constitute one of a number of similar plates 85 spaced equidistantly apart when the cabinet is divided into a plurality of units for the purpose of increasing its capacity or for convenient classification of its contents.

Each of the plates has at its upper edge 90 oppositely projecting lugs 8^a for its support upon the ledges and its ends are longitudinally slotted for the application of lazy tongs 10. The slots in the ends of the plates are preferably reenforced by strips of metal 95 12 fastened in correspondingly formed recesses and the intersecting bars of the lazy tongs which are pivotally connected to the plates at their upper extremities have pins or rollers at their lower ends which travel 100 in said slots.

It will be apparent from the above that each of the filing units of the case has two opposed surfaces one of which is movable with relation to the other, and that by the 105 lazy tong connection between the plates and the back of the case the several surfaces are compelled to move in unison relative to those to which they are opposed, whereby to widen or reduce the spaces between them.

Extending oppositely from the surfaces of each unit and out of alignment with relation to each other are sets of pins 13 which in the operation of the invention are conjointly used for the suspension of the maps or drawings 14 which to this end are provided with correspondingly arranged perforations 15 as best shown in Figure 5 of the drawings.

10 The length of the pins is such that when the surfaces from which they project are moved apart, a space is formed between their ends through which the maps or drawings may be moved up or downwardly for their placement on or removal from either set.

15 The pins are provided at their ends with laterally projecting retention shoulders 13^a preferably formed by flattening their opposite sides.

20 Used in conjunction with the pins for the placement or removal of the maps are two keepers 16 each consisting of a strip of metal having notches in one of its edges which are arranged in correspondence with the spaced arrangement of the two sets of pins on the opposed surfaces of one of the filing units.

25 Each strip has two series of notches 17 and 18 of different widths alternately arranged, one width corresponding to the thickness of the pins rearward of their shoulders and the other width exceeding the thickness of the pins across said shoulders.

30 The series of notches of each strip alternate reversely with relation to those of the other so that when the strips are placed together the wide notches of either are alined with the narrow ones of the other.

35 In the operation of my invention the maps or drawings are suspended from the pins on the opposite surfaces of one of the filing units by placing them on one of the sets after the surfaces are moved apart, it being understood that the opposite set will enter the corresponding perforations of the maps 45 when the surfaces are subsequently moved together.

40 By forming the perforations in the maps or drawings at substantially equal distances from the upper edges thereof, the different articles suspended from the pins are made 50 separately accessible irrespective of their proportions and while the present invention does not include any particular means for forming the perforations, it appears appropriate to mention at this point that a special device having a plurality of punches at fixed distances apart and gauges which determine the position of a map or drawing with relation thereto, will be found to be 55 a practically indispensable adjunct to the cabinet.

60 The perforations of the maps may be reinforced by pieces of cardboard or the like or they may be formed in tabs which are 65 attached at the edges of the maps.

For convenience in identifying the different articles on file, they can be provided with upwardly projecting tabs as shown at 19 in Figure 5 which bear the name, subject or number of the same.

70 In order to remove one of the maps filed in the cabinet, the two keepers 16 are placed over the pins at opposite sides thereof after which the surfaces of the unit in which the map is filed are moved apart.

75 The alternate arrangement of the wide and narrow notches of the keepers will retain one of them on either set of pins, with the result that after the surfaces have been separated to the extent that a space is formed 80 between the ends of the pins the maps between the keepers will be free to be removed through said space while the maps at opposite sides thereof are retained upon the sets of pins by the respective keepers as shown 85 in Figure 3 of the drawings.

90 A map may be placed in a selected position with relation to the maps already on file in a similar manner by placing the two keepers together in the selected space between the two maps, then separating the surfaces as before and placing the map to be filed upon one of the sets of pins through the space between them.

95 Having thus described my improved filing cabinet in the most practical form at present known to me, I desire it understood that variations in the construction and arrangements of its parts may be resorted to without departing from the spirit of the invention as defined in the following claims.

100 What I claim and desire to secure by Letters-Patent is:

1. A filing device having two opposed surfaces one of which is movable relative to the other, sets of suspension-members projecting oppositely from the surfaces to conjointly support an article placed between them, and means cooperating with said members to automatically retain a selected number of suspended articles on either set when the surfaces are moved apart.

105 2. In a filing device, two opposed surfaces having a connection for the movement of one in constant parallel relation to the other, sets of suspension-members projecting oppositely from the surfaces to conjointly support an article placed between them, and means cooperating with said members to automatically retain a selected number of suspended articles on either set when the surfaces are moved apart.

110 3. In a filing cabinet, a series of plates providing pairs of opposed surfaces, and interconnected to be simultaneously separated from each other, sets of suspension members projecting oppositely from the opposed surfaces to conjointly support an article placed between them, and means cooperating with said members to automatically retain a se- 115

- lected number of suspended articles on either set when the plates are moved apart. 6. A filing device having two opposed surfaces one of which is movable relative to the other, sets of pins projecting oppositely from said surfaces, and alternately arranged out of alinement with each other, each pin having retention shoulders at its end, and keepers each having two series of notches of different widths alternately arranged to receive the pins of the two sets respectively, and reversely arranged with relation to those of the other keeper. 25
4. In a filing cabinet, a series of plates comprising pairs of two opposed surfaces 5 and interconnected for their simultaneous separation from each other in constant parallel relation, sets of suspension-members projecting oppositely from the opposed surfaces to conjointly support articles placed 10 between them, and means cooperating with said members to automatically retain a selected number of suspended articles on either set when the plates are moved apart. 30
5. A filing device having two opposed surfaces one of which is movable relative to the other, sets of pins projecting oppositely from said surfaces out of alinement with respect to each other, each pin having retention-shoulders at its end, and two keepers each 15 having two series of notches of different widths, arranged to receive the pins of the two sets respectively, and reversely arranged with relation to those of the other keeper. 35
- 20
7. A filing device having two opposed surfaces one of which is movable relative to the other, non-alined sets of suspension members projecting oppositely from the surfaces to conjointly support an article placed between them, and means cooperating with 40 said members to automatically retain a selected number of suspended articles on either set when the surfaces are moved apart.

In testimony whereof I have affixed my signature.

GEORGE H. BARNHART.
